UNITED STATES PATENT OFFICE.

CHARLES L. KELLY, OF SANTA FE, NEW MEXICO.

WINDOW-SCREEN.

1,082,339.

Specification of Letters Patent. Patented Dec. 23, 1913.

Application filed February 18, 1913. Serial No. 749,192.

To all whom it may concern:

Be it known that I, CHARLES L. KELLY, a citizen of the United States, residing at Santa Fe, in the county of Santa Fe and

5 State of New Mexico, have invented certain new and useful Improvements in Window Screens, of which the following is a specification, reference being had therein to the accompanying drawing.

10 This invention relates to window screens, and has for its object the production of a screen which is adapted to wind and unwind as the sash is raised or lowered.

Another object of this invention is the 15 production of a roller containing box which is adapted to be placed upon the sill of the window and held firmly in engagement therewith by means of a plurality of standards.

20 A still further object is the production of a roller containing box which is provided with novel and efficient means for facilitating the insertion of the roller therein.

With these and other objects in view this 25 invention consists of certain novel combinations, constructions, and arrangements of parts as will be hereinafter fully described and claimed.

In the accompanying drawings:—Figure 30 1 is a view in elevation of the window frame and sash showing the roller containing box in longitudinal section. Fig. 2 is a transverse section through the roller containing box and the window sash and frame. Fig. 3 is a view in elevation of the window sash and frame and also the roller containing box showing a portion of the screen member withdrawn therefrom. Fig. 4 is a section similar to Fig. 3 and taken at right angles 35 thereto. Fig. 5 is a detail perspective of a portion of the roller containing box. Fig. 6 is a perspective view of one of the standards. Fig. 7 is a view in elevation of a portion of the band member. Fig. 8 is a section 40 taken on the line 8—8, of Fig. 7.

Referring to the accompanying drawings by numerals it will be seen that the device is used in combination with the ordinary window frame 1 and sash 2. The window 45 frame 1 is provided with the usual sill 3 which is adapted to carry the roller containing box. This roller containing box is provided with a plurality of end members 4 and 5 to which the bottom 6, back 7, and top 8 are fixedly secured. The top 8 is provided at one side with the longitudinally

extending cut-away portion 9 which constitutes the slot 10. The end 4 is provided with the transversely extending groove 11 which terminates in the pocket portion 12. 60 Mounted within the end 1 there is provided a plate 13 which is provided with a groove 14 and pocket 15 which are adapted to register with the groove 11 and pocket 12. The end 5 is provided with the ordinary socket 65 16 which is adapted to receive the pintle 17 of the roller. After the pintle has been placed within this socket 16 the pintle 17 is placed within the groove 11 and guided into the pocket 12. The pintle or journal 70 carries the ordinary spring and roller upon which the screen 18 is rotatably mounted. By use of the socket 16 and the pocket 12 it will be seen that the roller and spring will be held in their correct position within 75 the roller containing box.

The screen 18 passes through the slot 10 and is provided with the U-shape band member 19 which is clamped upon its outer end. This band member 19 is provided with 80 a plurality of inverted V-shape openings 20 which are adapted to engage the nails 21 which are carried by the sash 2. It will be seen that in mounting the screen upon the sash in the manner described when the sash 85 is raised it will unwind the screen and will cover the opening caused by raising the window and will in this manner prevent any insects from entering the room. When, however, the window is closed the screen will 90 be wound upon the roller and will in this manner cause the same to be placed entirely out of the way. If, however, it is desired to detach the screen from engagement with the sash the band 19 may be moved upward 95 at which time the band may be lifted from engagement with the nails 21 and the head will pass through the opening 20.

In order to close the front portion of the roller containing box the ends are provided 100 with the vertically extending grooves 22 in which the sliding door 23 is adapted to be positioned.

After the roller containing box has been placed upon the sill 3 and the outer end of 105 the screen has been mounted upon the sash 2 a vertical standard 24 which is provided with an angular bracket 25 and a retaining bracket 26 is placed upon the upper portion 110 of the roller containing box at each end thereof. The angular bracket 25 is then secured to the box by any suitable means and

the retaining bracket 26 is fastened to the window frame. By this means it will be seen that the roller containing box will be securely held in position upon the sill and 5 will be prevented from being drawn up when the window is raised.

Whenever it is desired to move the box from the window sill the vertical standard may be disengaged from the frame by re- 10 moving the band 19 from engagement with the sash and the device may be removed from engagement with the window.

Having thus described the invention what is claimed as new is:—

15 A device of the class described comprising an elongated housing, said housing provided with end blocks, one of said blocks being provided with a transversely-extending groove terminating in a pocket, a metallic 20 reinforcing plate surrounding said groove

and constituting means for protecting the same, said end blocks provided with vertically-extending grooves extending at right-angles to said first-mentioned groove, a top closure plate for said housing provided with 25 a longitudinally-extending opening, a curtain placed within said housing, a roller supporting said curtain and fitting in said first-mentioned groove, said curtain provided with a reinforced end, said reinforced end 30 provided with tapering apertures adapted to fit over the securing means whereby said curtain may be attached to a window sash.

In testimony whereof I hereunto affix my signature in presence of two witnesses.

CHARLES L. KELLY.

Witnesses:

W. C. DOWNING,
W. H. ROGERS.
